attorney.

UNITED STATES PATENT OFFICE.

NICHOLAS I. HOEY, OF WILMORE, KENTUCKY.

RAILWAY SWITCH-LAMP.

1,335,503.

Specification of Letters Patent. Patented Mar. 30, 1920.

Application filed August 29, 1919. Serial No. 320,682.

To all whom it may concern:

Be it known that I, NICHOLAS I. HOEY, a citizen of the United States of America, and a resident of Wilmore, in the county of 5 Jessamine and State of Kentucky, have invented a certain new and useful Improvement in Railway Switch-Lamps, of which the following is a specification.

This invention relates to railway switch 10 or signal lamps, or, more particularly speaking, to lamps used in connection with switches, semaphores and other similar signal devices in railroad service.

The object of the invention herein is to 15 provide a signal-lamp with lenses or bull's-eyes that are adapted to be circularly-shifted on the lamp-barrel for directly projecting a full beam of light, whether clear white or colored, so as to get a full-face view 20 of the lens at the desired points in advance on curves where heretofore such full-face view has been impossible at any appreciable distance from the switch-lamp whereby the engine crew might easily see in ample time 25 the state of the switch or track ahead at the time of entering or while on a curve and thereby saving the train from accident at the switch that can be easily avoided in the use of my improved circularly-adjustable 30 or rotary-shiftable lens lamp.

The details of structure will be fully hereinafter described in connection with the accompanying sheet of drawings, in which—

Figure 1 is a plan view of a section of 35 railway-track taken at a switch that includes a straight line of siding and a curve in the main-line entered by said switch at a station or elsewhere suitable for said siding, the switch-rails in this view being 40 shown closed for maintaining the said main-line intact and the switch-lamp being the ordinary one and with its stationary lenses in their ordinary right-angled relation to each other as now in general use; Fig. 2, a 45 view similar to Fig. 1 and, also, with the switch-rails closed for maintaining the main-line intact the same as in Fig. 1, but with the lenses shifted or adjusted on the lamp-barrel so as to direct a full-face view 50 of the clear or white lens that faces the curve up to a point of entrance to said curve or at the farthest point of safety along said curve and embodying my invention therein; Fig. 3, an elevation of the barrel or shell, 55 with the top or crown in section, and with the circularly adjustable or shiftable lens-

carriers and their clamping-bands shown in dotted-lines; Fig. 4, a horizontal section taken on a line across the center of the lamp-barrel, on line x , x , of Fig. 5, or that of the 60 lenses and their shiftable carriers; Fig. 5, a perspective view of the two corresponding shiftable lens-carriers forming the important feature of my invention herein; Fig. 6, a plan view of one of the clamping-bands 65 used for holding said lens-carriers in adjusted position; Fig. 7, a perspective view of the clamping-band shown in Fig. 6; and Fig. 8, a detail elevation of one of the two 70 gaskets used in the space or annulus between the said shiftable lens-carriers and the lamp-barrel.

In Fig. 1 I have shown a switch-portion 75 of a track with a lamp of the ordinary type now in general use at switches in set-position for a curve in the main-line. The lamp has its lenses mounted stationary on the barrel or shell of its light-chamber, at right-angles to each other, there being two red and two clear or white lenses, indicated by 80 "R" and "W" respectively. In said Fig. 1 the red and white lenses are shown as they should be, the reds being diametrically in line with each other and the whites likewise. The switch-points being closed for the 85 main-line, the clear or white lenses should, of course, be directed toward the curve on the left and the straight portion of the main-line on the right-side of the view, indicating safety in both directions along the 90 main-line, and they are so shown in this view, but it will be observed that the full-face of the lens to the left can only be seen at a short distance up the curve, possibly 95 two-hundred yards at the most, as indicated at the star "B", the view upon the said left lens along the curve being gradually lessened or phased down to a very thin edge of light hardly discernible by the engine crew within a safe distance from the switch, or 100 at least with any degree of accuracy so as to positively avoid danger or accident in the event of an unintended open switch at the said siding and especially in connection with a train approaching from the left 105 along said curve. A train approaching on the straight portion of the main-line, from the right, can, of course, get a full-face view of the lens, whether red or white, facing to the right, either in the old or new 110 form of lamp. But, if there should be a continuous or an S curve to the right, in-

stead of a straight track, then the same conditions as to lessening the light of the lens, whether red or white, would result and danger of entering an open switch from the main-line on the right always present and accidents always possible, especially to trains running at high speed. It is quite evident that the light of the left lens of the lamp in the ordinary form in Fig. 1 could not be seen to advantage at the point of safety (about three-fourths of a mile) indicated by the star "A" at the point of beginning of the curve or at some distance along its course from the switch, or the farthest possible for safety of the traffic along said curve from the left.

To remedy the weakness in the use of said ordinary form of switch-lamp I provide lens-carriers 1 and 2, made of sheet-metal and each one semicircular, with their opposite vertical edges flanged at 3 to stiffen them and to form convenient handles for use in their sliding or shifting adjustment. Both carriers are alike and each has a pair of tubular lens holder-rims 4 projecting from it, one lens "R" being a red one and the other "W" a clear or white one, as ordinarily provided in switch-lamps. These lens-carriers are mounted on the lamp-barrel 5, which latter has openings or windows 6 therein to align or register with said lenses when the carriers are in place, such openings 6 being of somewhat larger area than that of the lenses so as to allow for the desired circular adjustment or shifting of the carriers around the lamp-barrel to suit the relative positions of the lenses on the said lamp-barrel for the various degrees of curves and the distance of safety that the full-face view of the lens shall be provided for up the curve.

Ordinarily, curves of fifteen degrees, more or less, are frequently present at switches in main-lines of railways, and the lens carriers or segments of my improvement herein should, therefore, have an arc of movement either way, horizontally, around the circular barrel of the lamp, of seven degrees, more or less, whereby the desired full-face view of the lens facing the curve can be had at least three-fourths of a mile or so up the curve from the switch, and thus the engineer can readily and accurately see what the actual condition or nature of the signal is ahead of him, and, if red, indicating an open switch or danger, he can at once proceed to put his train under control to avoid accident at the switch. The star "A" in Fig. 2 indicates the farthest point on the curve at which the desired full-face view of the lens can be properly seen from the approaching engine, and is the same as the star "A" in Fig. 1.

Clamping bands or collars 7 are provided for use in securing the lens-carriers in ad-

justed position on the lamp-barrel or shell, free, however, to be readily loosened for other adjustment or detachment for repairs or the like when desired. These bands are parted or split at 8 and turned outwardly at their ends 9 for the use of screws or bolts 10 to contract or draw them into tight place around the upper and lower edges of the said lens-carriers, the latter being bordered at top and bottom by the beads or ribs 11 made in the lamp barrel or shell 5, as best seen in Fig. 3.

In order to provide for the ready adjustment or shifting of the lens-carriers, one independent of the other around the outer surface of the lamp-barrel, I leave a suitable space or annulus 12, seen in Fig. 4, and in that space I provide, also, a pair of duly spaced rectangular open gaskets or frames 13 made of thin material, one of which is disclosed in detail plan in Fig. 8, and, in using place in Fig. 4 to make the lamp-chamber air-tight and free from leakage.

In setting the lens-carriers in place on the lamp-barrel to suit the desired degree of curve approaching the switch the lens-carriers are brought toward each other along one pair of adjoining edges, as best seen in Fig. 4, whereby the red and white lenses of the two carriers approach each other at one side and depart from each other at the other side of the axis of the internal lamp, so that the lenses can be full viewed from both directions along the main line whether it be a curve at one side of the switch-lamp and a straightway ahead on the other side, or a curve at both sides of the switch-lamp. It will be observed that the two lens-carriers are independent of each other so that their lenses can be set apart at the desired distances on the lamp-barrel to suit conditions at both sides of the lamp in the main-line at the switch, one lens frequently requiring more adjustment in one direction than its companion or like lens does on the other carrier in the other direction in relation to the switch and its lamp, especially when curves of different degrees are at both sides of the switch.

The device is equally useful in connection with semaphores and other railway-signaling appliances where accuracy of the character of signals and their color are important and of a very serious and valuable nature, and such as are met in the use of my invention.

The lamp is easily assembled with my shiftable lenses, in order to replace them or to adjust them for any purpose required of them and they add no material expense to the lamp.

I claim:

1. In a railway switch-lamp, a shell or barrel having light emitting orifices therein, a pair of semicircular, circularly-adjust-

able slide-plates or carriers also having light emitting orifices therein, red and clear white lenses in the orifices of each of the said pair of slide-plates or carriers, contractible bands or collars adapted to hold or clamp said slide-plates or carriers in adjusted position on the said barrel whereby the red lenses or the clear white lenses may be brought into full bull's-eye signaling-view from the switch at any point desired, substantially as shown and described.

2. In a railway switch-lamp, a cylindrical shell or barrel having light port-holes therein, a pair of semicircular, circularly adjustable, segmental slide-plates or carriers also having coinciding light port-holes therein but supplied with suitable red and clear lenses, vertical outwardly-turned flanges at

the opposite ends of the said adjustable segmental slide-plates or carriers, clamping bands or collars adapted to encircle the upper and lower extended ends of the said segmental slide-plates or carriers and to secure them in adjusted position on the said barrel to suit the degree of curve in a main-line of track for directly and fully throwing a beam of light in full face or bull's-eye signal form and strength, and an open rectangular frame or gasket intervening between the said shell or barrel and the said adjustable segmental slide-plates or lens-carriers to prevent currents of air or other leakage into the lamp-chamber, substantially as set forth.

NICHOLAS I. HOEY.
